United States Patent Office

Des. 188,430
Patented July 19, 1960

188,430

CHAFING DISH STAND

Victor J. Bergeron, Orinda, Calif.
(20 Cosmo Place, San Francisco, Calif.)

Filed Mar. 28, 1960, Ser. No. 59,892

Term of patent 14 years

(Cl. D44—10)

FIG. 1

The broken lines are for illustrative purposes only.

I claim:

The ornamental design for a chafing dish stand, as shown and described.
